TIE LINER AND METHOD OF MAKING THE SAME

Filed June 18, 1928

UNITED STATES PATENT OFFICE

JOHN V. MOORE, OF PAWTUCKET, RHODE ISLAND, ASSIGNOR TO MOORE FABRIC COMPANY, OF PAWTUCKET, RHODE ISLAND, A CORPORATION OF RHODE ISLAND

TIE LINER AND METHOD OF MAKING THE SAME

Application filed June 18, 1928. Serial No. 286,432.

This invention relates to a liner for neckties and to an improved method of making the same.

It is the general object of my invention to provide a tie liner which is woven and processed to the desired shape and outline, and which possesses the necessary resilience to resist permanent creasing or folding.

A further object is to provide a liner of varying width but having full selvage edges at all points, said edges being preferably of increased thickness.

In the preferred form, my improved liner also has a thickened and more substantial middle portion.

A preferred form of the invention is shown in the drawings in which

Fig. 1 is a plan view of my improved liner; and

Fig. 2 is a cross sectional elevation, taken along the line 2—2 in Fig. 1.

Referring to the drawings, my improved tie liner is preferably woven to shape on a narrow ware loom, the end portions 10 and 11 being relatively wide, and the band portion being relatively narrow.

The liner may be conveniently woven in a narrow ware loom having a fan reed, by which the width of the fabric may be varied as the weave progresses, and I also preferably provide means by which the number of picks of filling per inch may be varied directly with the width of the liner. That is, as the width of the liner increases, the number of picks of filling per inch also increases, thus providing greater stiffness in the wider parts of the tie liner.

The fabric may be formed of any suitable material but I find it satisfactory to use a weft of hard twisted worsted yarn and a warp of hard cotton yarn, the warp threads preferably being alternately reversed in twist across the width of the fabric. This reversal of twist balances the shrinkage and prevents the shrunken and finished liner from receiving a curvilinear set.

The particular weave of the fabric may be widely varied and in itself forms no part of my present invention. Preferably the selvage edge portions 14 are of increased

thickness, as indicated in Fig. 2, and the middle portion 16 may also desirably be of increased thickness. This increased thickness may be produced in any convenient manner as by forming the edge and middle portions of two ply construction and the intermediate portions of single ply construction.

After forming my improved tie liner by weaving the same to shape in a narrow ware loom, the liner is completed by a process of shrinking and finishing by which the length of the liner may be very substantially reduced while at the same time the thickness and resilience of the liner is correspondingly increased. It is common practice in the manufacture of my improved liner to weave the liner from two to three times as long as the finished product, thereafter shrinking the same to thirty or forty per cent of the original length.

This excessive shrinkage renders the liner highly elastic and also gives it such body and resilience that it satisfactorily resists permanent creasing or folding while in use in a necktie. The warp and weft threads used in weaving the fabric are commonly non-elastic in themselves, but the fabric acquires elasticity in the shrinking and finishing process, which is ordinarily carried out by immersing in hot water or some chlorine solution.

The provision of thicker edges and a thickened middle portion increases the apparent substance of the liner, while the thinner intermediate portions reduce the bulk thereof and also reduce the amount of material used in making the liner.

The tie liner may be formed of single ply fabric, or the middle and edge portions may be two ply or multi-ply while the intermediate portions remain single ply. The worsted weft gives snap or life to the liner, while the shrunken hard twisted cotton warp gives lengthwise resilience.

Having thus described my invention and the advantages thereof, I do not wish to be limited to the details herein disclosed, otherwise than as set forth in the claims, but what I claim is:—

1. An integral woven tie liner having a

100

narrow band portion and broader end portions, and having two full selvage edge portions, the middle and selvage portions being of integral increased thickness and being separated by material of less thickness.

5 2. An integral woven tie liner having a narrow band portion and broader end portions, and having two full selvage edge portions, said liner being inherently elastic 10 when finished and being woven of warp threads of hard twisted cotton and of weft threads of hard twisted worsted, and both warp and weft threads being substantially non-elastic.

15 3. The combination in an integral woven tie liner as set forth in claim 2, in which the warp threads are alternately of opposite twist.

20 4. An integral woven tie liner formed entirely of a single piece of woven material and having a narrow band portion and broader end portions, the longitudinal edges of said band and end portions having full continuous integral finished woven selvages and said single piece of material being woven 25 with longitudinal portions of less thickness adjacent the integral selvage edge portions of said liner.

25 In testimony whereof I have hereunto affixed my signature.

JOHN V. MOORE.
